Assor to

DES. 1943

The Lowell Manufacturing Company, of the same place.

Letters Patent No 1943 Dated May 10, 1863.

Design for a Carpet Pattern.

The schedule referred to in these Letters Patent and making part of the same.

To all whom it may concern:

Be it known that I, Elmer J. Key, of Lowell,
in the County of Middlesex and State of Massachusetts, have origi-
nated and designed a new Pattern for Carpets or other fabrics, of which
the following is a full, clear and exact description, reference be-
ing had to the accompanying drawings, making part of this spec-
ification.

The set figure 1, rests on the ground A, which has
an irregular border and is enclosed by the diamond frame
2, which is composed of a double row of blocks.

Outside the frame 2, are the chains of rings 3, 3.

4, 4, are cross shaped figures surrounded by mottled
work enclosed by the many sided frames 5, 5.

The chains 3, 3, overlap parts of the frames 5, 5.

B, B, are set figures similar to fig. 1, and rest on the
grounds 6, 6, which are enclosed by spring work and diamond frames
similar to 2.

C, is a set figure surrounded by mottled work enclosed
by a frame similar to frames 5, 5.

Running parallel with the sides of the diamond frames
enclosing grounds 6, 6, are rope like bands.

The space between these bands and the chains of rings

before mentioned is occupied by Persian leaf-work and a small rosette.

The remaining figures are either duplicates or sections of figures similar to those before specified.

The colors employed for the different portions of the design, may be varied to suit the taste and wish of the manufacturer.

Claim.

What I claim as my invention and desire to secure by Letters Patent, is, The Design or Pattern, for Carpets or other fabrics, herein set forth.
